DES. 2029

Michael F. Ryan, of New York, N.Y.

Letters Patent No. 2029-Dated Feb. 7-1865.

Design for a Badge or Breast-Pin.

The design referred to in these letters Patent and making part of the same.

State whom it may concern:

Be it known that I, Michael F. Ryan, a citizen of the City, County and State of New York, have invented or produced a new and ornamental Design for Badge and Breast Pin; and I do hereby declare that the following is a full, clear and exact description thereof, which I will warrant to others skilled in the art to make and use the same referred to, being had to the accompanying drawing forming a part of this application.

The drawing presents a perspective view of this invention.

This design consists in an American Eagle, holding in its bill an anchor emblem of hope, and in one of its talons a bundle of arrows while the other talon grasps a chain which connects with a pin, the head of which is spear shaped or barbed. The breast of the eagle is embellished by an escutcheon containing the coat of arms of Ireland.

A representation of an eagle having its wings about half

2 spread and its head turned towards one side - In its beak it holds an anchor, and with one of its talons it grasps a bundle of arrows, while its other talon grasps a chain, which connects with the harp. The head of this pin is barbed, a wing is the same the shape of an arrow head.

The breast of the eagle is embellished. On each wing is a shield which contains a harp, surrounded by three lions, preventing the coat of arms of Ireland.

I claim a new and desire to secure by Letters Patent

A design for a breast pin as herein shown and described.
